His ATTORNEY.

UNITED STATES PATENT OFFICE.

MARTIN CARROLL, OF KANSAS CITY, MISSOURI.

SIDEWALK-VENTILATOR.

No. 896,273.

Specification of Letters Patent.

Patented Aug. 18, 1908.

Application filed October 8, 1907. Serial No. 396,424.

To all whom it may concern:

Be it known that I, MARTIN CARROLL, a citizen of the United States, residing at Kansas City, in the county of Jackson and State 5 of Missouri, have invented certain new and useful Improvements in Sidewalk-Ventilators, of which the following is a specification.

My invention relates to improvements in sidewalk ventilators.

10 The object of my invention is to provide an improved form of sidewalk ventilator by which air and light may be readily admitted to the area below the sidewalk, novel means being provided by which, in stormy weather, 15 water and dirt may be prevented from entering the area through the ventilator.

The novel features of my invention are hereinafter fully described and claimed.

In the accompanying drawings illustrative 20 of my invention—Figure 1 is a perspective view of my improved sidewalk ventilator as it is mounted in a concrete pavement, a portion of the top of the ventilator being broken away. Fig. 2 is a vertical sectional view, 25 taken transversely across the ventilator on the dotted line *a*—*b* of Fig. 3. Fig. 3 is a cross section taken on the dotted line *e*—*f* of Fig. 2. Fig. 4 is a vertical sectional view taken on the dotted line *c*—*d* of Fig. 2. Fig. 30 5 is a view similar to Fig. 2 the closure for the ventilating openings being shown in the closed position in Fig. 2 and in the open position in Fig. 5.

Similar characters of reference denote simi- 35 lar parts.

The ventilator comprises preferably, a rectangular, horizontal hollow body provided with a closed top 1 and vertical side walls 2. The top 1 may be provided with translucent 40 glass plates 3 embedded horizontally in cement or concrete 4 which is supported by horizontal rods 5, which in turn rest at their ends upon horizontal flanges 6 provided in the top 1 and extending along the sides of a 45 rectangular opening 7 provided in the top of the body 1. One or all of the side walls 2 are provided each with one or more transverse openings 8, best shown in Fig. 4, and which permit air to enter the area below the side- 50 walk. Inwardly extending from each side wall 2 is a horizontal flange 9. A similar flange 10 extends horizontally along the outer side of each side wall 2.

Preferably the upper sides of the flanges 9 55 and 10 and the lower sides of the openings 8 incline downwardly and outwardly in the

same plane, so that water entering the openings 8 will run outwardly instead of into the area under the sidewalk. Extending transversely across the openings 8 upon the upper sides and adjacent the inner edges of the flanges 9 are provided flanges 11, each of which extends vertically in a corresponding longitudinal groove, provided in the lower side of a closure 12 secured by hinges 13 to 60 the inner side of the flange 9. The closure 12 is preferably in the form of a quarter round, the flat side of which, provided with the groove fitting the flange 11, rests upon the upper side of the flange 9 when the closure 12 is in the closed position shown in solid 65 lines in Figs. 3 and 4.

The curved side of each closure 12 is disposed at the inner sides of curved screens 14 extending one across the inner end of each 70 ventilating opening 8. One closure 12 is shown in the drawings. If other closures are employed they are constructed in the same manner as the one illustrated.

Each closure on the side which is the inner 75 side when the closure is in the closed position, is provided with a hand hold, such as a hook 15, by which the closure may be swung to and from the closed position. The closure 12, when in the closed position, serves as a support which prevents the screen 14 from being inwardly bent by sticks or other objects which may be accidentally or otherwise inserted through the openings 8. The closure 12 is preferably provided on its inner side 80 with a depression 16 in which the head of the hook 15 is located. Such disposal of the hook 15 lessens its liability to injury.

The underside of the body of the ventilator is preferably provided with four downwardly 90 extending flanges 17, joined at their respective ends to form a rectangle and which, when embedded in the concrete 18, forming the pavement, prevent lateral movement of the ventilator. When the ventilator is set 95 in the concrete 18, the upper sides of the flanges 10 are preferably flush with the upper side of the concrete pavement 18.

Various modifications of my invention within the scope of the appended claims may 100 be made without departing from its spirit.

Having thus described my invention what I claim and desire to secure by Letters Patent is:—

1. A sidewalk ventilator having a horizontal, hollow body closed at the top and having 110 a ventilating opening in one side wall, a hori-

zontal flange extending outwardly from said wall the upper side of said flange and the lower side of said opening inclining outwardly and downwardly in the same plane, 5 and a hinged closure for the inner end of said opening.

2. A sidewalk ventilator having a horizontal, hollow body closed at the top and having a ventilating opening in one side wall, a 10 screen across the inner end of said opening, a hinged closure for the inner end of said opening, and a horizontal flange extending outwardly from said wall the upper side of said flange and the lower side of said opening being 15 in the same plane.

3. A sidewalk ventilator having a horizontal, hollow body closed at the top and having a ventilating opening in one side wall, a horizontal flange extending inwardly from said 20 wall, the upper side of said flange and the lower side of said opening being in the same plane, and a closure for the inner end of said opening hinged to said flange and resting thereon when in the closed position.

25 4. A sidewalk ventilator having a horizontal, hollow body closed at the top and having a ventilating opening in one side wall, a horizontal flange extending inwardly from said wall, the upper side of said flange and the lower side of said opening being in the same plane, and a vertical flange on the upper side of said inwardly extending flange and extending across said opening.

35 5. A sidewalk ventilator having a horizontal, hollow body closed at the top and having a ventilating opening in one side wall, a horizontal flange extending inwardly from said wall, the upper side of said flange and the lower side of said opening inclining downward and outward in the same plane, and a vertical flange extending across said opening upon the upper side of said inwardly extending flange.

40 6. A sidewalk ventilator having a horizontal, hollow body closed at the top and having a ventilating opening in one side wall, a horizontal flange extending inwardly from said wall, the upper side of said flange and the lower side of said opening inclining in the same plane downwardly and outwardly, a vertical flange extending across said opening upon the upper side of said inwardly extend-

ing flange, and a closure for said opening hinged to said inwardly extending flange.

7. A sidewalk ventilator having a horizontal, hollow body closed at the top and having a ventilating opening in one side wall, a horizontal flange extending inwardly from said wall, the upper side of said flange and the lower side of said opening being in the same plane, a vertical flange extending across said opening upon the upper side of said inwardly extending flange, a closure for said opening hinged to said inwardly extending flange, and a screen across said opening.

65 8. A sidewalk ventilator having a horizontal, hollow body closed at the top and having a ventilating opening in one side wall, a horizontal flange extending inwardly from said wall, a horizontal flange extending outwardly from said wall the upper sides of said flanges and the lower side of said opening inclining downwardly and outwardly in the same plane, and a closure for the inner end of said opening hinged to said inwardly extending flange which supports said closure in the 70 closed position.

75 9. A sidewalk ventilator having a horizontal, hollow body closed at the top and having a ventilating opening in one side wall, a horizontal flange extending inwardly from said wall, a horizontal flange extending outwardly from said wall, the upper sides of said flanges and the lower side of said opening inclining downwardly and outwardly in the same plane, a vertical flange extending across said opening upon the upper side of the inwardly extending flange, and a closure for the inner end of said opening hinged to said inwardly extending flange, said closure 80 when in the closed position having its lower side resting upon the upper side of said inwardly extending flange, said lower side of said closure having a longitudinal groove for receiving said vertical flange when the closure 85 is in the closed position.

95 In testimony whereof I have signed my name to this specification in presence of two subscribing witnesses.

MARTIN CARROLL.
